Patented June 27, 1922.

By Ira J. Wilson.

Atty.

UNITED STATES PATENT OFFICE.

HARRY R. TRAPHAGEN, OF ROCKFORD, ILLINOIS, ASSIGNOR TO EMERSON-BRANT-INGHAM COMPANY, OF ROCKFORD, ILLINOIS, A CORPORATION OF ILLINOIS.

COLTER.

1,421,111.

Specification of Letters Patent. Patented June 27, 1922.

Application filed June 16, 1919. Serial No. 304,378.

To all whom it may concern:

Be it known that I, HARRY R. TRAPHAGEN, a citizen of the United States, residing at Rockford, in the county of Winnebago and State of Illinois, have invented certain new and useful Improvements in Colters, of which the following is a specification.

This invention pertaining in general to 10 agricultural machinery, has more particular reference to colters, such as are used with plows in the well known manner. It is common practice to support a colter in front of a plow body through the agency of a 15 colter stem and bracket, the stem being adjustably attached to the plow frame, and capable of adjustment thereon to change the position of the colter with respect to the plow body. It is well recognized that 20 improper positioning of the colter with respect to the plow body is inimical to good plowing, and it is often found difficult to secure and maintain a colter in the desired position, mainly due to the construction of the 25 connection between the colter bracket and the stem, and because of the imperfections and variances of the casting and from wear occasioned thereby after the plow has been in use.

30 The present invention aims, primarily, to provide a colter connection of improved construction which remedies the objections and disadvantages following from constructions heretofore used, and it also aims to provide 35 an improved colter bearing, the advantages of which will be mentioned hereinafter.

As regards the connection between the colter bracket and stem, it is an object of my invention to provide a construction which 40 will enable quick assembling and will insure against lost motion and play between the parts, which will be strong and durable for all practical purposes and well adapted for all conditions and requirements of service, 45 and which is constructed in such simple manner as to be capable of production at a comparatively low cost.

Another object resides in the provision of 50 a colter connection of the character in mind which permits of a limited amount of oscillation for the colter and is so constructed as to permit assembling of the parts in only their correct relative relation.

Other objects and attendant advantages 55 will be appreciated as the invention becomes

better understood by reference to the following description when considered in connection with the accompanying drawing, in which—

Figure 1 is a side elevation of a colter and 60 its stem embodying my improvements; and Fig. 2, a plan view, partly in section.

Referring to the drawing, the well known parts designated generally, comprise a colter disk 5, a bracket or yoke 6 and stem 7, the 65 upper end of the latter being adapted for adjustable attachment to a plow frame in any suitable manner. It will be noted that the stem has a depending end 8 offset to the rear of its main upright portion and that 70 this end 8 is tapered longitudinally. The yoke at the junction of its arms 9 and 11 is shaped to provide a head 12 having a central bore 13 tapered longitudinally in conformity to the taper of the portion 8. In the manufacture of these parts, the stem 7 and the tapered portion 8 are forged by dies, and the yoke 6 is a casting with a cored central opening 13. By reason of this construction, 75 it is not customary to machine finish any surface, since it will be manifest that the tapered opening or socket 13 of the yoke may be moved onto the stem portion 8 sufficiently to secure as tight a joint as desired.

It will be noted, however, that the yoke 6 80 should be free to oscillate on the stem portion 8 so that the colter will caster when turning a corner, but will be held firmly against wobbling and movement vertically, such as would be occasioned by a loose floppy joint between the colter bracket and stem. 85

I have now provided means for securing the colter head yoke 12 in any position on the stem 8 to which the said head may be adjusted, but permitting the desired oscillation, and it will be manifest that with the inclusion of suitable means, preferably a set collar in this connection, the yoke head may be immediately adjusted on the stem portion 8 to a satisfactory working position, free 90 from lost motion, and held in such position by the set collar. I employ a set collar 14 disposed on the stem portion 8 in an opening 15 intermediate the ends of the head 12 so that the set collar when secured to the stem 8 will prevent movement of the head either 95 up or down on the stem. Viewing Fig. 1, it will be noted that the bore of the set collar also is tapered to fit the tapered stem portion 8 so that when the fastening nut 16 is 100

95

100

105

110

tightened the collar, which closely and fittingly embraces the tapered stem, will be secured thereto in a very substantial manner. In order to limit the extent of oscillation of the yoke 6, I have provided the set collar 14 with a lug 17 disposed in an arcuate opening 18 in the head 12, the oscillation being limited by contact of this lug 17 with the ends 19 of said opening. Viewing Fig. 1, it will be noted that the lug 17 is arranged at the bottom side of set collar 14, and it follows that by reason of this location of the lug 17, there is only one way in which the set collar may be inserted in the opening 15 with its tapered bore in alignment with that of a head 12. Thus in assembling the parts, especially by an unskilled person, it is impossible to place the set collar in position with its tapered opening reversed from what it should be. If after a long period of usage the connection becomes worn, it may be quickly adjusted to take up the wear, simply by loosening the set screw 16 and moving the head 12 and set collar 14 upwardly on the stem 8 and tightening the set screw to hold the parts in the new position.

My improvements also relate to the construction of the colter bearing in which I have aimed to provide a practical and serviceable construction capable of production at a minimum cost. Viewing Fig. 2, it will be seen that a bolt 21 joins the arms 9 and 11 of the yoke and is threadingly engaged in the arm 11, and equipped at its headed end with a suitable bolt lock 22. A cone shaped spindle 23 on the bolt 21 is in abutting relation at its ends with the arms 9 and 11 and clamped in fixed relation thereto by tightening of the bolt 21. The hub 24 of the colter disk 5 revolves freely on the cone spindle 23. It will be noted that there are a number of washers 25 on the bolt 21, between the arm 11 and adjoining end of the cone spindle 23. By means of one or more washers of suitable thickness placed in this manner on the bolt 21, the cone spindle 23 may be clamped rigidly between the arms 9 and 11 and in such relation to the bearing 24 as to obtain the proper cooperative relation between the cone, spindle and hub. That is, due to the inevitable variances in the manufacture of these parts, the cone spindles 23 in different bearings, when properly associated with the colter hub 55 will be located at different positions between the arms 9 and 11; and by use of washers 25 properly placed, the cone spindle may be rigidly secured in the proper position very quickly and easily. It will be obvious that the washers may be removed and placed at either end of the cone spindle as may be required, to take up wear.

The novel features above described enable the production of colters or caster wheels of this character at a comparatively

low cost, as special provision is made for securing the proper assembly of parts regardless of variances incidental to castings. At the same time the parts are so designed that they give maximum strength and durability in the performance of the work for which they are intended.

It should be understood that while I have illustrated and described but a single working embodiment of my improvements, various changes might be made in the construction and arrangement without departing from the spirit and scope of the invention as expressed in the appended claims. With reference to the claims, it should be understood that the terms "stem," "colter" or "colter disk" are used as representative of either a strictly colter construction on one embodying a caster wheel instead of a colter blade, or any similar construction of this character in which the connection or combination claimed has the same function.

I claim:

1. The combination with a colter disk, of a supporting bracket therefor, a stem having a longitudinally tapered end, said bracket shaped to provide a longitudinally tapered opening adapted to receive said tapered end on the stem, the tapered end of the stem being of sufficient length to permit adjustment of the bracket to a position in which it fittingly seats on said stem, and a set collar having a tapered opening and adapted to fit said tapered stem and be secured thereto for holding the bracket in operative position thereon.

2. The combination with a colter disk, of a supporting yoke or bracket therefor having a head with a longitudinally tapered opening, a longitudinally tapered stem fitting in said opening, a set collar for holding the yoke head against movement in both directions longitudinally on the stem, and a lug on the set collar closer to one face than to the other and operative between opposed faces on the yoke head for limiting oscillation of the yoke on the stem.

3. The combination with a colter disk, of a longitudinally tapered stem, a yoke carrying the colter, the head of the yoke having a tapered opening adapted to receive said tapered stem and shaped intermediate its ends to provide an opening for the reception of a set collar, and a set collar having a tapered bore and positioned on the tapered stem in said opening in the yoke head for holding said head against movement in opposite directions longitudinally on the stem.

4. The combination with a colter disk, of a longitudinally tapered stem, a bracket supporting the colter disk and having a head provided with a tapered opening adapted to fittingly receive said tapered stem, and a part secured to the stem and adjustable lengthwise thereon and co-operating with

said head of the colter yoke or bracket for preventing movement of said head longitudinally on the tapered stem and also for limiting the extent of oscillation of said head with respect to the stem.

5. The combination of a colter yoke of the character described, a colter disk, a single cone spindle interposed between the arms of the yoke, a hub for the colter disk having

a longitudinally tapered journal revolvably fitting the cone spindle, and means operative between the arms of the yoke and said cone spindle for rigidly securing the latter to said arms and for adjusting the spindle longitudinally of its axis and with respect to the 15 arms of the yoke for taking up wear between the spindle and disk hub.

HARRY R. TRAPHAGEN.
